CATHODE-RAY SIGNAL-GENERATING TUBE

Harold M. Lewis, Great Neck, and Rudolf C. Hergenrother, Beechhurst, N. Y., assignors to Hazeltine Corporation, a corporation of Delaware

Application November 28, 1936, Serial No. 113,200

12 Claims. (Cl. 250—153)

This invention relates to television systems, and more particularly to cathode-ray tube signal-generating systems.

Heretofore there have been developed various types of cathode-ray signal-generating tubes comprising, in general, an elongated evacuated envelope including at one end an electron gun for generating and accelerating a stream of electrons and focusing it into a beam, a photo-sensitive target and collecting anode disposed in the other end of the envelope, and means for deflecting the beam to scan the target upon which is projected the image of a scene to be transmitted. The target most widely in use comprises a thin sheet of dielectric, such as mica, having on one side a metallic or other conductive coating and on the other a coating of highly conductive photosensitive substance usually comprising a silver-caesium-oxygen mixture or compound, the exact molecular structure of which is not clearly understood but which probably comprises a colloidal suspension of metal in a simple or complex oxide forming an insulating binder. There results a mosaic of infinitesimal condensers having as a common electrode the backing coating of the dielectric sheet and as the other electrodes the photosensitive particles. When an image of a scene is projected on the photosensitive mosaic, there results a surface electron emission which at each elemental area is proportional to the light intensity at that point. As a result, the elemental condensers become charged to degrees proportional to their respective illumination.

In the operation of a device of the type described, the cathode ray is caused to scan the mosaic, and, while the effect of the cathode ray on the mosaic is complicated by the generation of secondary electrons tending to mask the primary photoelectric emission, the ultimate result is that the cathode-ray beam periodically discharges each elemental condenser in succession, causing modulation or variation in the secondary electron current to the collecting anode due to the discharge currents of the condensers, these modulation currents constituting a measure of the variation of the light intensity of the scanned scene.

The signal-generating tube of the type described has a number of disadvantages. In the first place, because of the opacity of the target, the target must be mounted in the tube at an angle to the incident cathode ray and the scene projected thereon through the side of the tube, resulting in a so-called "keystone" effect because

of the angularity of the cathode-ray beam, requiring some form of compensation. Furthermore, because of the large secondary electron emission effect, the secondary electrons emitted from any given element of the mosaic tend to bombard and modify the charge of the adjacent elements of the mosaic, thus reducing the efficiency of the device.

It is an object of this invention to provide an improved cathode-ray tube signal-generating system which overcomes one or more of the above-described disadvantages and is relatively efficient in operation.

It is another object of the invention to provide an improved cathode-ray tube signal-generating system of simplified construction and of substantially higher photoelectric sensitivity than the arrangements of the prior art.

It is a specific object of the invention to provide an improved cathode-ray tube signal-generating system in which the scene to be scanned may be projected directly on the enlarged end of the envelope of a cathode-ray tube.

A cathode-ray signal-generating tube of a system in accordance with this invention comprises an evacuated envelope of conventional shape including an electron gun for generating and accelerating a stream of electrons of constant intensity and focusing it into a beam and a photo-sensitive target and a collecting anode disposed in the enlarged end of the envelope remote from the electron gun. The target consists of a metallic or other conductive plate or film coated with a homogeneous substance having, in the absence of light, such a high specific resistance, that is, such a low specific conductivity, as to be what is ordinarily termed an insulator but having a substantial volume photoconductive property; that is, the property of substantially lowered volumetric resistance or substantially higher specific conductivity when illuminated. The output circuit of the device includes connections between the collecting anode and the conductive layer of the target including a high impedance which is, nevertheless, a small fraction of the impedance of the cathode-ray beam circuit at signal frequencies which, with conventional electron gun structure, is of the order of 100 megohms. With such an arrangement, the projection of an image of a scene on the photosensitive film results in a variation of the resistance of the film over the surface, corresponding to variations in the intensity of the light throughout the scene. If now, the cathode ray is caused to scan the scene, the resistances of successive incremental portions of

the coating are varied in accordance with the intensity of their respective illumination. The electron current of the beam, which remains constant, divides between the conductive element 5 of the photosensitive target and the collecting anode, the latter component comprising secondary electron emission from the target and the division of current varying from instant to instant in accordance with illumination of the incremental portions being scanned. There is thus produced, in effect, a signal-modulated current flowing between the target and the collector anode, providing a signal which may be transmitted for reproduction of a scene at the television receiver. 10 Preferably, the conductive layer of the target is disposed directly on the inside surface of the enlarged end of the envelope as a semitransparent metallic film and the photosensitive coating is disposed on the film on the side facing the electron gun. With such an arrangement, the scene may be projected directly on the end of the envelope from the camera, or the like, having an optical axis coincident with the axis of the envelope, thereby eliminating distortion effects due to 20 the angularity of the target with respect to the cathode ray.

For a better understanding of the invention, together with other and further objects thereof, reference is had to the following description 30 taken in connection with the accompanying drawing, and its scope will be pointed out in the appended claims. Referring to the drawing: Fig. 1 is a schematic diagram of a complete television transmitting system including a cathode-ray signal-generating system in accordance with the present invention; Fig. 2 is a fragmentary view in perspective of the enlarged end of a cathode-ray tube showing the cathode-ray target partly in section, while Fig. 3 is a perspective 35 view of a modified form of a cathode-ray target for embodiment in the cathode-ray tube system according to the present invention.

Referring now more particularly to Fig. 1 of the drawing, there is illustrated a complete 40 transmitting television system including a camera or projector 9 and a cathode-ray signal-generating tube 10 constructed and arranged in accordance with the present invention. The cathode-ray tube 10 comprises an elongated envelope 11 having a narrow cylindrical neck 11a and an enlarged conical end portion 11b. An indirectly heated cathode 12 (the heater of which is not shown) is mounted in the end of the portion 11a, adjacent to which are disposed a control grid 13, a focusing anode 14, and a collecting anode 15, the elements 12, 13, 14, and 15 constituting together what is known in the art as an electron gun. The collecting anode 15 may comprise a metallic film or coating on the inner surface 55 of the envelope 11, as shown. The tube 10 is also provided with a cathode-ray photosensitive target 16 disposed adjacent the end surface of the portion 11b of the envelope, and described in more detail hereinafter. Disposed about the portion 11a of the tube envelope are the scanning or deflecting coils 17 for deflecting the cathode ray of the electron gun rectilinearly to scan the image projected on the cathode-ray target 16. Suitable operating potentials are supplied to the several electrodes of the tube 10 from a voltage divider 18 connected to a suitable source, indicated as plus and minus and preferably grounded at its positive terminal. The circuit of the control grid 13 includes the series 60 blocking resistors 19, 20, and 21. The connec-

tion to the photosensitive target 16 is preferably made to a point on the voltage divider 18 positive with respect to that to which the second anode 15 is connected and, as shown, includes a load resistor 22 of high resistance or equivalent 65 element having a high impedance which is, nevertheless, a small fraction of the impedance of the cathode-ray beam circuit at signal frequencies which, with a conventional electron gun structure, is of the order of 100 megohms. 10

In order to block out the cathode ray during the retrace portion of the scanning cycle, there is provided a so-called pedestal generator 23 which is coupled across the resistor 20 through coupling condensers 24. The scanning coils 17 are 15 energized from the line-frequency generator 25 and the frame-frequency generator 26, which are controlled by timer 27 which also synchronizes the pedestal generator 23 with generators 25 and 26. Also coupled to the timer 27 is a mixed line- 20 and frame-frequency synchronizing generator 28 for supplying the proper synchronizing impulses to the signal to be transmitted in order to control the corresponding scanning circuits of the receiver. The video signals picked up across the resistor 22 in the circuit interconnecting the cathode-ray target 16 and collecting anode 15, the synchronizing impulses generated by the generator 28, and the block-out or pedestal signals generated by the device 23 are combined 25 and amplified in a mixing or modulation amplifier 29, the output of which is connected to a modulator 30 supplied also with carrier-frequency oscillations from an oscillator 31. The resulting modulated high-frequency carrier generated by the modulator 30 is passed through a power amplifier 32 and thence delivered to the antenna circuit 33-33.

With the exception of the signal-generating system including cathode-ray tube 10, which is described in more detail hereinafter, the elements of the above-described system are conventional in their construction and operation, so that a detailed description thereof need not be included here. However, in brief, assuming that 40 an image of a scene to be transmitted is projected upon the target 16 and that the scanning coils 17 are energized with scanning currents of appropriate frequency and wave form, there appears in the output circuit between the scanning target 16 and collecting anode 15 and across the resistor 22 video-frequency voltages which are a measure of the intensity of illumination of the successive incremental areas of the target 16, as they are scanned by the cathode ray generated by the electron gun structure 12, 13, 14. These signals are impressed upon the modulation amplifier 29 which also receives line- and frame-frequency synchronizing impulses from the generator 28 and pedestal or block-out signals from 45 the generator 23, the several generators being inter-related by the timer 27 to maintain the synchronizing impulses impressed upon the transmitted carrier in synchronism with the scanning waves generated and impressed upon 50 the scanning coils 17 of the transmitter tube. These combined signals are amplified in the modulation or mixing amplifier 29 and supplied to the modulator 30, wherein they are converted into modulated carrier-frequency oscillations 55 which are amplified in the power amplifier 32 and radiated by the antenna circuit 33-33.

As stated above, the target 16 is preferably formed on the inside surface of the enlarged end 60 of the envelope 11. The structure of this target 75

is shown more clearly in Fig. 2 which illustrates the target, partly in section, on a greatly magnified scale in order to render it capable of illustration, as the layers or films of the target are of microscopic thickness. As shown in Fig. 2, the target 16 comprises a metallic film, such as nickel, deposited over the entire inside end surface of the tube 11 of a thickness only sufficient to be opaque, as shown by the portions 16a-16a of the section. The film is formed with a rectangular window 16b approximately the size of the image to be projected on the target and there is deposited thereon on the side facing the electron gun a metallic or other conductive film 16c much thinner than the surrounding coating 16a. This coating is sufficiently thin as to be semitransparent, that is, capable of transmitting of the order of 20% or more of the received illumination and preferably transmitting of the order of 50% of such illumination. On the semitransparent film 16c is deposited a layer 16d of photoconductive material; that is, material in which incremental changes in illumination are accompanied by substantial incremental changes 25 in the conductivity of the material, which relationship is hereinafter termed the coefficient of photoconductivity.

In the operation of the target 16 as shown particularly in Fig. 2, the scene to be scanned is projected from the camera or projector 9 through the semitransparent film 16b, and the light transmitted therethrough causes the photo-conductivity of the layer 16d to vary throughout, proportionally to variations of the intensity of the illumination of the image of the scene. The portion 16d of the target 16 is scanned by the cathode ray in response to the excitation of the scanning coils 17, with the result that successive incremental portions of the layer 16d constitute 40 effective resistances which vary in accordance with the intensity of illumination of the corresponding incremental areas of the scene to be transmitted. The variation in resistance of successive incremental portions of the film 16d 45 varies the division of the electron current of the cathode ray (which, as stated above, remains constant) between the conductive film 16a, 16c and the collecting anode 15, the latter component comprising secondary electron emission from the target 16. The distribution of the electron current 50 of the cathode ray is such that increase in illumination of the elemental portion being scanned is accompanied by an increase in the potential of the target 16 in a positive sense and 55 an increase in the potential of the anode 15 in a negative sense; that is, current flowing in the circuit interconnecting these electrodes is modulated or varied in accordance with variations in the resistance of the film 16d throughout its 60 extent so that they may be utilized as output electrodes. Preferably, the target 16 is utilized as the high potential output electrode since its capacitance to ground is considerably less than that of the collecting anode 15. By including 65 the load resistor 22 in circuit with the target 16 and collecting anode 15, modulation voltages are developed across the resistor 22, which are utilized to modulate the locally generated carrier wave for broadcast transmission.

70 The photoconductivity characteristic of the film 16d of the target of this invention is to be distinguished from the photosensitive properties of substances heretofore utilized in cathode-ray tubes included in television systems. The distinction between this substance and the fluores-

cent screens of cathode-ray tubes used in television receivers is clear in that the essential characteristic of the latter material is that it emits light upon excitation by a cathode ray, which property is in no way related to its photosensitivity. The distinctions between the photosensitive material used in the tube of this invention and that heretofore used in signal-generating tubes are not so superficial, and the differences may be best appreciated by a direct 10 comparison of the materials:

(1) The photosensitive material utilized in this invention has, when unexcited, such a high specific resistance, that is, low specific conductivity, that it falls in the class of substances usually 15 termed insulators, while that of the prior art is a highly conductive material.

(2) The characteristic property of the photosensitive material utilized herein is that its volume-conductivity changes with the intensity of 20 illumination, involving what is believed to be a displacement of the electrons within the atoms from their normal positions, setting up a strain which is released by the displacement current flowing when a voltage is applied, as by a cathode ray, restoring the material to its normal non-conductive state. On the other hand, the material of the prior art exhibits purely surface photoelectric emission, that is, absorption of the light quanta at the surface of the material and 30 release therefrom of free electrons. While both of these photoelectric effects are modified or masked by the secondary electron emission resulting from the bombardment of the target by the cathode ray, the essential phenomena on 35 which the operation of the photosensitive targets depend are fundamentally different.

(3) The photosensitive material of the prior art, relying on a surface effect, is extremely thin, normally having a thickness of from 50 to 100 40 molecular diameters, while the photosensitive layer of this invention, relying on a volumetric effect, is relatively extremely thick. While the actual thickness of the photosensitive layer of this invention is very small, of the order of one 45 ten-thousandth of an inch, this represents a layer of a thickness of many millions of molecules, that is, a film of a thickness of an entirely higher order of magnitude than that of the photosensitive films of the prior art. 50

(4) The photosensitive material of this invention comprises a homogeneous coating of a single compound, while that of the prior art comprises a mosaic, for example, the usual complex silver-caesium-oxygen mixture which is 55 thought to be a colloidal suspension in a simple or complex metallic oxide.

(5) The prior art photosensitive target comprises essentially a large number of infinitesimal condensers which are charged by the illumination of the projected image and discharged by the cathode ray, while the photosensitive material of this invention is essentially a resistance which varies throughout its extent and which, because of the thinness of the film, is not seriously affected by edge effects of the material surrounding the cathode-ray spot at any particular instant.

(6) As in the arrangements of the prior art, 70 the operation of the photosensitive target involves a certain integrating process in that illumination of each incremental portion for a finite time is required to change its conductive properties to a substantial extent, this time being 75

supplied by the interval between successive scanings of the target by the cathode ray.

In selecting the photosensitive materials which are to be utilized in the improved signal-generating tube of this invention, the following properties are important: first, of course, is the coefficient of photoconductivity. Heretofore it has been recognized that many substances possess such property, best known of which is perhaps selenium. However, there is a large number of other materials whose photoconductive properties have been measured. Certain of these are mentioned and their particular properties discussed in the text "Photoelectric Phenomena" by Hughes & Du Bridge, McGraw-Hill, 1932, beginning at page 321. Secondly, it is important that the material have a very high specific resistance approaching that of material ordinarily classed as an insulator, in order that the impedance of the photosensitive film may be comparable with that of the other circuit elements in the load circuit of a signal-generating tube. Further, it is desirable, though not essential, that the photosensitive material be highly refractory; that is, stable at the high temperatures to facilitate baking out the signal-generating tube during the exhaust to remove the occluded gases. It has been discovered that, as between crystalline photoconductive substances, the coefficient of photoconductivity varies approximately with the index of refraction with respect to light far removed from the absorption frequency, a property of materials as to which information is more generally available. It has been determined that only those substances having indices of refraction of the order of two or greater have coefficients of photoconductivity of sufficient magnitude to be useful in signal-generating tubes of the type to which this invention refers.

In general, it has been found that the most suitable photosensitive materials are included in the metallic compounds of the halogens or of the oxygen-sulphur sub-group of the periodic table including the metallic halides, oxides, and sulphides. There follows a partial table of those materials, all of which are crystalline, which are suitable for use as the photosensitive film in a signal-generating tube of this invention:

50	Substance	Formula	Index refraction
55	Antimony trioxide	Sb ₂ O ₃	2.1
	Antimony trisulphide	Sb ₂ S ₃	3.2
	Cadmium oxide	CdO	2.5
	Cadmium sulphide	CdS	2.53
	Chromium oxide	Cr ₂ O ₃	2.5
	Copper iodide	CuI	2.3
	Cuprous oxide	Cu ₂ O	2.7
	Diamond	C	2.4
	Lead oxide	PbO	2.5
	Lead chloride	PbCl ₂	2.2
	Lead tungstate	PbWO ₄	2.27
60	Mercuric sulphide	HgS	2.8
	Manganese oxide	MnO	2.2
	Nickel oxide	NiO	2.18
	Thallic chloride	TlCl	2.2
	Thallic iodide	TlI	2.8
	Titanium oxide	TiO ₂	2.5
	Zinc oxide	ZnO	2.0
65	Zinc sulphide	ZnS	2.4
	Zirconium oxide	ZrO ₂	2.1
	Zirconium silicate	ZrSiO ₄	2.02

It has also been found that fluorescent material utilized in cathode-ray receiving tubes, such as that described in German Patent No. 440,350 to Riedel and de Haen, commercially available as television compound #60K of Riedel-de Haen, distributed by Pfaltz and Bauer, New York city, can be used as a photosensitive material. It is believed that this compound comprises essentially

zinc sulphide and cadmium sulphide activated by a trace of silver and copper. However, this substance has a lower coefficient of photoconductivity than chemically pure zinc sulphide, included in the foregoing table.

Thus, it is seen that there is provided by this invention a novel and improved cathode-ray tube signal-generating system, in which the scene may be projected on the target coaxially with the normal position of the cathode ray, thus avoiding the keystone effect due to the angularity of the target with respect to the cathode ray. Further, the novel cathode-ray tube signal-generating system, according to this invention is of simplified construction and highly efficient in operation.

In Fig. 3 there is shown a target 116 of modified form in which the photosensitive film 116d is deposited directly on an opaque metallic plate 116a disposed in the envelope in any suitable fashion as by mounting it in a plane angular to the cathode ray, in which case the image of a scene is projected upon the target through a window in the side of the envelope in the conventional manner.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television signal-generating system including a cathode-ray signal-generating tube comprising an elongated evacuated envelope, an electron gun disposed in one end of said envelope for generating and accelerating a stream of electrons of constant intensity and focusing it into a beam, a photo-sensitive target electrode in the path of the path of the electron beam and adapted to have an image of a scene projected thereon, said target comprising a layer of conductive material and a layer of photoconductive material disposed thereon on the side facing said electron gun, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam. 40

2. A cathode-ray signal-generating tube comprising an elongated evacuated envelope, an electron gun disposed in one end of said envelope for generating and accelerating a stream of electrons and focusing it into a beam, a photo-sensitive target electrode in the path of the electron beam and adapted to have an image of a scene projected thereon, said target comprising a layer of conductive material and a layer of homogeneous material disposed thereon on the side facing said electron gun, said latter layer being of extremely low specific conductivity when unexcited but of substantially increased specific conductivity when illuminated, an anode disposed to collect secondary electrons emitted by said target, means for deflecting said beam to scan the image projected on said target, and an output circuit interconnected said anode and said conductive layer and having an impedance at signal frequencies which is a small fraction of the impedance of said beam. 75

3. A cathode-ray signal-generating tube comprising an elongated evacuated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin layer of homogeneous crystalline material disposed thereon on the side facing said electron gun, said latter layer having a high coefficient of photoconductivity, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
4. A cathode-ray signal-generating tube comprising an elongated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin layer of homogeneous refractory material disposed thereon on the side facing said electron gun, said latter layer having a normally low specific conductivity and a high coefficient of photoconductivity, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
5. A cathode-ray signal-generating tube comprising an elongated evacuated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin coating thereon consisting essentially of a refractory metallic halide having a high coefficient of photoconductivity, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
6. A cathode-ray signal-generating tube comprising an elongated evacuated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin coating thereon on the side facing said electron gun, said coating consisting essentially of a refractory metallic compound of an element of the oxygen-sulphur subgroup having a high coefficient of photoconductivity, an anode disposed to collect secondary electrons emitted by said target, means for deflecting said beam to scan the image projected on said target, and an output circuit intercon-
- necting said anode and said conductive layer and having an impedance at signal frequencies which is a small fraction of the impedance of said beam.
7. A cathode-ray signal-generating tube comprising an elongated evacuated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin coating thereon consisting essentially of a refractory metallic oxide having a high coefficient of photoconductivity, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
8. A cathode-ray signal-generating tube comprising an elongated evacuated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin coating thereon consisting essentially of a refractory metallic sulphide having a high coefficient of photoconductivity, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
9. A cathode-ray signal-generating tube comprising an elongated evacuated envelope, an electron gun disposed in one end of said envelope for generating and accelerating a stream of electrons and focusing it into a beam, a photosensitive target electrode in the path of the electron beam and adapted to have an image of a scene projected thereon, said target comprising a layer of conductive material and a thin coating thereon consisting essentially of a refractory zinc sulphide having a high coefficient of photoconductivity, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
10. A cathode-ray signal-generating tube comprising an elongated evacuated envelope enlarged at one end, an electron gun disposed in one end of said envelope for generating and accelerating a stream of electrons and focusing it into a beam, a conductive first coating on the inside enlarged end surface of said envelope, said coating being at least semitransparent, and a second coating of photoconductive material superposed on said first coating, said coatings constituting a cathode-ray target electrode and adapted to have an image of a scene projected thereon from a direction opposite to that of said electron gun, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.

- output circuit interconnecting said anode and said conductive layer and having an impedance at signal frequencies which is a small fraction of the impedance of said beam.
- 5 11. A cathode-ray signal-generating tube comprising an elongated evacuated envelope enlarged at one end, an electron gun disposed in one end of said envelope for generating and accelerating a stream of electrons and focusing it into a beam,
- 10 a thin metallic film deposited on the inside enlarged end surface of said envelope, said film being at least semitransparent, and a thin coating of homogeneous material disposed thereon having a high coefficient of photoconductivity, said film
- 15 and coating constituting a cathode-ray target electrode and adapted to have an image of a scene projected thereon from a direction opposite to that of said electron gun, an anode disposed to collect secondary electrons emitted by said target, means for deflecting said beam to scan the image projected on said target, and an output circuit interconnecting said anode and said conductive layer and having an impedance at signal frequencies which is a small fraction of the impedance of said beam.
- 20
- 25

12. A cathode-ray signal-generating tube comprising an elongated evacuated envelope enlarged at one end, an electron gun disposed in one end of said envelope for generating and accelerating a stream of electrons and focusing it into a beam, 5 an opaque coating on the enlarged end surface of said envelope having a rectangular window, a thin metallic film deposited on said inside end surface and coextensive with said window, and a thin coating of homogeneous refractory material disposed on said metallic film and having a high coefficient of conductivity, said film and its coating constituting a cathode-ray target electrode and adapted to have an image of a scene projected thereon from a direction opposite to that of said electron gun, an anode disposed to collect secondary electrons emitted by said target, means for deflecting said beam to scan the image projected on said target, and an output circuit interconnecting said anode and said conductive layer 10 and having an impedance at signal frequencies which is a small fraction of the impedance of said beam.
